APPARATUS FOR MAKING WALLBOARDS

William G. Brubacher, Montreal, Quebec,
CanadaApplication May 10, 1944, Serial No. 534,865
In Canada May 29, 1943

13 Claims. (Cl. 92—54)

1

This invention relates to an apparatus for making cavitated wall board, and more specifically to an apparatus for making such wall board from organic fibrous materials such as those produced from wood, straw, sugar cane, etc.

In my copending application Serial No. 430,422, filed February 11, 1942, now Patent No. 2,370,393, granted February 27, 1945, I have disclosed an apparatus of the continuous type for manufacturing cavitated wall boards from fibrous materials of the organic type referred to. Such apparatus is particularly adapted for the quantity production of cavitated board in factories of substantial size.

An important object of the present invention is to provide a relatively small apparatus for manufacturing individual cavitated boards and which is adapted for use in relatively small manufacturing plants.

A further object is to provide such an apparatus which is adapted to receive a charge of the initial material and to be quickly and easily operated to produce a single cavitated board.

A further object is to provide such an apparatus which is compact in size and easy to install and operate to produce cavitated boards in relatively small quantities.

A further object is to provide such an apparatus which is particularly efficient for the manufacture of wall boards from fibrous materials of the character referred to, and wherein the boards will be uniform, of low density and substantial thickness to provide a maximum insulating value, and of relatively light weight, etc.

Other objects and advantages of the invention will become apparent during the course of the following description.

In the drawings I have shown one embodiment of the invention. In this showing—

Figure 1 is a central vertical sectional view through the apparatus, parts being shown in elevation.

Figure 2 is an enlarged horizontal sectional view on line 2—2 of Figure 1.

Figure 3 is an enlarged fragmentary vertical sectional view on line 3—3 of Figure 1.

Figure 4 is an enlarged detail sectional view through the tube holder looking in the same direction as in Figure 3, parts being shown in elevation.

Figure 5 is a detail sectional view on line 5—5 of Figure 4, and,

Figure 6 is a similar view on line 6—6 of Figure 4.

Referring to Figure 1 the numeral 10 designates a vertical casing or vat closed at its lower end by a head 11. As will become apparent later, the upper and lower ends of the vat 10 form chambers 12 and 13 for a purpose to be described.

Intermediate its ends the vat 10 has its walls perforated as at 14 for the flow of liquid into a drainage chamber 15. This chamber is formed at opposite sides of the vat by walls 16 welded or otherwise secured to the walls of the vat 10. At the other sides of the vat, the chamber 15 is defined by doors to be referred to later. Each of the walls 16 at the bottom thereof defines a guide 17 for a purpose to be described.

Referring to Figures 2 and 3 the numeral 20 designates each of a pair of doors shaped in cross-section generally similar to the walls 16 and cooperating therewith to form continuations of the drainage chamber 15. Each of the doors 20 is adapted to be opened or removed for the introduction into and the removal from the vat 10 of a forming device indicated as a whole by the numeral 21 and referred to in detail later. Any suitable means may be employed for providing for the opening or removal of the doors 20. For example, each door 20 may be provided at its upper end with a flange 22 normally arranged beneath a keeper 23 welded or otherwise secured to the vat 10. The bottom of each door 20 may be provided with a similar flange 24 arranged beneath a keeper 25 slotted as at 26 for the reception of a bolt 27 carrying a thumb nut 28. It will be apparent that the nuts 28 may be loosened to permit the keepers 25 to slide downwardly free of the flanges 24 of both doors, whereby the lower edge of each door may be swung outwardly a short distance and then pulled downwardly to be removed from the vat.

The forming device 21 comprises a generally rectangular frame 30 split as at 31 (Figure 2) to form angular complementary sections 32. Any suitable preferably quick releasable means is employed for clamping the two frame members 32 in their normal positions shown in Figure 2. Such a quick detachable device is indicated as a whole by the numeral 33 and since such device is conventional, it need not be referred to in detail.

Opposite sides of the frame 30 are apertured as at 35 (Figure 4) in aligned relation to receive forming tubes each of which is indicated as a whole by the numeral 37 and comprises complementary tube sections 38 and 39 the adjacent edges of which are sloped as at 40 whereby each tube section is relatively wedge shaped. When the respective ends of the tube sections are flush

as shown in Figure 4 the tube will be in circular form as shown in Figures 5 and 6. The tube section 38 is provided with a central web 41 receivable between spaced webs 42 carried by the tube section 39. The engagement of these web elements prevents lateral movement of the tube sections with respect to each other as will be apparent. The web elements have their free edges sloped in planes parallel to the slope of the junction 40 of the tube elements 38 and 39 as shown in Figure 4. The webs 42 are apertured adjacent one end as at 43, while each of the webs 41 is similarly apertured adjacent the opposite end of the tube as at 44, these apertures being provided for engagement with pulling elements to pull the tube sections out of the frame 30 after a board has been formed in a manner to be described.

During the formation of each board, the forming device is arranged within the vat between the chambers 12 and 13. The frame 30 is preferably identical in shape and size to the cross-sectional shape and size of the vat 10, the upper and lower ends of the vat being fixed with relation to each other by the walls 16 welded thereto and by any other suitable bracing means if desired.

An upper plunger 48 is vertically reciprocable in the chamber 12. This plunger is carried by a piston rod 49 having a piston 50 at its upper end reciprocable in a hydraulic or other fluid pressure cylinder 51. A four-way valve 52 is provided with branch pipes 53 and 54 leading to the respective ends of the cylinder 51 and is supplied with pressure fluid from a suitable source through a pipe 55. The valve 52 has a conventional exhaust port (not shown) for exhausting either end of the cylinder 51 when the other end is connected to the pressure source. Upward movement of the plunger 48 is limited by stops 56 engageable with a flange 57 secured to the upper end of the vat 10. The plunger is provided with upwardly extending rods 58 carrying stops 59 adjustable as to position by suitable nuts 60 and engageable with the flange 57 to limit downward movement of the plunger 48 according to the desired thickness of the wall board to be made, as will become apparent. The plunger 48 is faced with a lower wire mesh screen 61.

The vat 10 is provided with a lower plunger 65 as shown in Figure 1, and both of the plungers 48 and 65 are perforated for a purpose to be described. The top face of the plunger 65 is provided with a fairly rigid wire mesh or other perforated sheet 66 and a finer mesh screen 67 overlies the element 66. The plunger 65 is carried by the upper end of a piston rod 68 extending through the head 11 and provided at its lower end with a piston 69 reciprocable in a cylinder 70. Pressures in the ends of the cylinder 70 are controlled by a four-way valve 71 similar in characteristics to the valve 52, through branch pipes 72 and 73 connected to the respective ends of the cylinder 70. Pressure fluid is supplied to the valve 71 through a pipe 74.

Downward movement of the plunger 65 is limited by suitable stops 78 carried by the head 11. The plunger 65 carries a plurality of depending rods 79 each of which carries a stop member 80 adjustable on the rod by a nut 81. The nuts 81 are adjusted in accordance with the desired thickness of the wall board to be made, as will become apparent.

The vat 10 is provided near the upper end of the chamber 12 with inlets 85 for the fiber stock

solution. This solution is relatively thin and may carry, for example, from .5% to 2% solids. Water from the solids flows by gravity through the perforations 14 into the drainage chamber 15 and from such chamber the liquid flows through outlet pipes 86 controlled by valves 87. Water will also flow through the elements 66 and 67 and through the perforations in the plunger 65, and such fluid is withdrawn from the bottom of the vat 10 through suitable pipes 88 provided with valves 89 and may be connected to a suitable source of suction. The valves 87 are closed while the vat is being charged with fibre stock, and are opened during the pressure operation, as will be referred to below.

Each board is formed within the forming device 21. A plurality of such devices are employed and after one board is formed the frame 21 is removed from the apparatus and another device 20 introduced thereinto. To facilitate introduction of the devices 21 into the vat 10 and their removal therefrom, supporting rails 90 and 91 may be arranged adjacent the respective sides of the apparatus. Assuming that the rails 90 are at the inlet side of the apparatus, a pusher 92 may be arranged over such rails and connected to a rod 93 which may be either manually or power operated.

The operation of the apparatus is as follows:

30 With the parts in the positions shown in Figure 1 a charge of material is introduced into the vat 10 through the inlets 85 while all of the drain valves are closed. When the predetermined amount of fibre stock has been run into the vat, 35 the valves 87 and 89 are opened, whereupon the valves 52 and 71 are operated either simultaneously or successively to introduce pressure into the remote ends of the cylinders 51 and 70 to move the piston 50 downwardly and to move the piston 69 upwardly. The two plungers 48 and 65 thus approach each other. During such operation, liquid will flow by gravity through the openings 14 to be discharged through the drainage chamber 15 and pipes 86. Liquid also will 45 flow through the perforated plunger 65 into the bottom of the vat 10 to be discharged through the pipes 88. As the plungers approach each other, therefore, the charge of material progressively becomes denser. The plungers are so shaped as 50 to be adapted to enter the top and bottom of the forming device 21 within the frame 30 and when the plungers reach their limits of movement as indicated approximately by the dotted lines in Figure 1, little liquid will remain in the body of 55 the fiber in the forming device 21. It will be apparent that pressure will be exerted against the fibrous material to express liquid therefrom, some of such liquid passing downwardly through the plunger 65 while some of it will be forced upwardly through the perforated plunger 48 to be discharged through the openings 14. The stops 59 and 80 will be positioned to arrest movement of the plungers at the proper point according to the desired thickness of the board. This board 60 will be defined by the woven wire members 61 and 67 and by the frame 30 and the tubes 37 will be embedded in the board.

Pressure will be maintained on the board element thus formed until all of the excess water 70 has drained from the apparatus. The valve 52 will then be operated to move the plunger 48 upwardly to the position shown in Figure 1. The newly formed board is now ready to be removed, as described below, and since the element 67 will have merely laid loosely on the plunger 65 it

will adhere to the board and will be removed therewith. The element 67 will determine the nature of the surface of the finished board and will adhere thereto within the bottom limit of the frame 30.

After the plunger 48 has been moved to the position shown in Figure 1, the nuts 28 (Figure 3) of both doors 20 will be loosened to drop the keepers 25, whereupon the respective doors 20 will be swung outwardly to a slight extent at their lower edges and then withdrawn downwardly. The pusher 92 is then operated to move the device 21 through the discharge door opening onto the rails 91. The pusher is then retracted and a new device 21 and tray 67 placed in position on the rails 90 and moved by the pusher into the apparatus. If desired, an empty frame 21 and tray 67 may be placed between the pusher 92 and the filled frame 21 within the apparatus, whereupon the pusher may be operated to move the empty frame into the apparatus and discharge the filled frame therefrom. The empty frame will move to the position shown in Figure 3 and the filled frame may be pulled by hand from the apparatus. The plunger 65 remains in operative position to support the newly formed board, and after the removal of such board, the valve 71 is operated to effect movement of the plunger 65 downwardly to its inoperative position shown in Figure 1. With an empty frame and its tray 67 in position in the apparatus, the doors 20 are then closed and the operation repeated to form a new board while the previously formed board is removed from its device 21.

The filled device 21 is placed upon a suitable table or the like whereupon hocks are inserted into the opposite ends of each tube 37 and engaged in the openings 43 and 44. The tube section 38 is pulled toward the left as viewed in Figure 4 while the tube section 39 is pulled toward the right. After the initial pulling of one of the tube sections the sloping surface 40 will provide for the contraction of the tube whereupon both sections thereof may be easily removed. The locking devices 33 (Figure 2) are then released whereupon the frame sections 32 may be easily removed from the formed board. The board, which is still supported by the sheet or tray 67, is then transferred to a suitable drying kiln, before or after which the screen 67 adhering to the board may be peeled therefrom.

From the foregoing it will be apparent that the present apparatus is simple and compact in construction and capable of relatively economical manufacture so as to render its use practicable in small plants to supply local trade with caviated fiber boards. The boards are relatively light and possess greater structural strength for the quantity of material therein than would be true without the cavitations left in the boards after the tubes 37 are removed therefrom. Such openings provide for a thicker board which also possesses high insulating value, and the making of the board under the pressure of the plungers provides a board of relatively great structural strength which is comparatively moisture proof and less subject to warping, expansion and contraction. The apparatus is easy to operate and the boards may be relatively rapidly made in successive operations of the apparatus.

Boards of different thicknesses readily may be made by employing forming devices 21 with tubes 37 of different sizes, and by suitably adjusting the stops 59 and 80. Thus while a single apparatus makes all boards of the same length and

width, boards of any desired thickness may be made with equal facility.

It is to be understood that the form of the invention herewith shown and described is to be taken as a preferred example of the same and that various changes in the shape, size and arrangement of parts may be resorted to without departing from the spirit of the invention or the scope of the subjoined claims.

10 I claim:

1. An apparatus for making fiber boards from a thin watery mix containing organic fibers, comprising a vertical vat, plungers vertically reciprocable in said vat and having horizontal forming faces, means for introducing the mix into said vat between said plungers when the latter are moved away from each other, and means for draining water from said vat as said plungers are moved toward each other to substantially reduce the water content of the mix and result in the formation of a board between the forming faces of said plungers, said draining means comprising a chamber surrounding said vat and the latter having openings therearound affording communication between the interior of said vat and said chamber.

2. An apparatus for making fiber boards from a thin watery mix containing organic fibers, comprising a vertical vat, plungers reciprocable in

30 said vat, means for introducing the mix into said vat between said plungers when the latter are moved away from each other, a forming device extending transversely of said vat intermediate the ends thereof, means for draining

35 liquid from the mix introduced into said vat, and means for moving said plungers toward each other to a position in proximity to said forming device to produce a solid board between said plungers when the liquid content of the mix

40 has been reduced to a predetermined extent, said draining means comprising a chamber surrounding said vat and the latter having perforations therearound above and in proximity to said forming device and communicating with said chamber.

3. An apparatus for making fiber boards from a thin watery mix containing organic fibers, comprising a vertical vat, plungers reciprocable in said vat, means for introducing the mix into said

50 vat between said plungers when the latter are moved away from each other, a forming device extending transversely of said vat intermediate the ends thereof, said device including a plurality of spaced forming elements, means for

55 draining liquid from the mix in said vat, and means for moving said plungers toward each other to positions in spaced relation to said spaced elements to form a resultant board between said plungers when the liquid content of the mix is

60 reduced to a predetermined extent, with said spaced elements embedded in the board, said draining means comprising a chamber surrounding said vat and the latter having perforations therearound above and in proximity to said forming device and communicating with said chamber.

4. Apparatus constructed in accordance with claim 3 wherein said forming device comprises a frame removably carrying said spaced elements

70 whereby removal of said elements will leave the resultant board with cavitations therein, said chamber having a wall removable to provide for the removal of said forming device from said vat.

75 5. Apparatus constructed in accordance with

claim 3 wherein said forming device comprises a frame formed of complementary sections, and means for clamping said sections together, said frame comprising opposite portions apertured to slidably support said spaced elements whereby the resultant board is left with cavitations there-in upon the removal of said spaced elements.

6. An apparatus for making fiber boards from a thin watery mix containing organic fibers, comprising a vertical vat, plungers reciprocable in said vat, means for introducing the mix into said vat between said plungers when the latter are moved away from each other, a drainage chamber arranged outwardly of said vat intermediate the ends thereof, said vat having apertures there-around for the flow into said chamber of liquid from the mix in said vat, and means for moving said plungers toward each other to form the fibrous material therebetween into a board when liquid in the mix has drained therefrom to a predetermined extent.

7. An apparatus for making fiber boards from a thin watery mix containing organic fibers, comprising a vertical vat, plungers reciprocable in said vat, means for introducing the mix into said vat between said plungers when the latter are moved away from each other, a forming device comprising a frame corresponding in shape and size to the cross-sectional shape and size of said vat, a door carried by said vat and adapted to be opened for the introduction of said forming device into said vat transversely thereof, said vat being provided with guideways for guiding and supporting said forming device in said vat, said forming device having relatively straight spaced forming elements extending thereacross, means for moving said plungers toward each other to positions spaced from said forming elements to form a resultant board between said plungers with said forming elements embedded therein, and means intermediate the ends of and extending around said vat for draining liquid therefrom.

8. An apparatus for making fiber boards from a thin watery mix containing organic fibers, comprising a vertical vat, plungers reciprocable in said vat, means for introducing the mix into said vat between said plungers when the latter are moved away from each other, a forming device comprising a frame corresponding in shape and size to the cross-sectional shape and size of said vat, a door carried by said vat and adapted to be opened for the introduction of said forming device into said vat transversely thereof, said vat being provided with guideways for guiding and supporting said forming device in said vat, said forming device having relatively straight spaced forming elements extending thereacross, a drainage chamber arranged outwardly of said vat, said vat being provided adjacent said forming device with apertures therearound for the drainage into said chamber of liquid from the mix in said vat, and means for moving said plungers toward each other to positions extending inwardly beyond the vertical limits of said forming device in spaced relation to said forming elements to form a resultant board having opposite faces defined by said plungers and with said forming elements embedded in such board.

9. An apparatus for making fiber boards from a thin watery mix containing organic fibers, comprising a vertical vat, plungers reciprocable in said vat, means for introducing the mix into said vat between said plungers when the latter are moved away from each other, one wall of

said vat being provided with a door, parallel guideways within said vat, a forming device insertable into said vat through said door to be slidably supported on said guideways, a drainage chamber arranged outwardly of said vat, said vat having apertures therearound just above said forming device for the drainage of liquid from the mix in the vat to said drainage chamber, and means for moving said plungers toward each other to positions in spaced relation adjacent said forming device to form a board therebetween, the upper plunger being apertured for the upward flow of liquid from between said plungers and thence outwardly into said drainage chamber through the apertures in said vat.

10. Apparatus constructed in accordance with claim 9 wherein said forming device comprises a frame having an inside size and shape corresponding to the size and shape of said lower plunger whereby the latter is adapted to enter the bottom of said forming device, and a finish-determining sheet resting on said lower plunger and adapted to adhere to the resultant board to be removed with such board and said forming device when the latter is withdrawn through said door.

11. Apparatus constructed in accordance with claim 9 wherein said forming device comprises a frame having an inside size and shape corresponding to the size and shape of said lower plunger whereby the latter is adapted to enter the bottom of said forming device, a finish-determining sheet resting on said lower plunger and adapted to adhere to the resultant board to be removed with such board and said forming device when the latter is withdrawn through said door, said lower plunger being apertured for the drainage of liquid downwardly therethrough, and a drain pipe connected to the bottom of said vat.

12. An apparatus for making fiber boards from a thin watery mix containing organic fibers, comprising a vertical vat, plungers reciprocable in said vat, means for introducing the mix into said vat between said plungers when the latter are moved away from each other, a drainage chamber arranged outwardly of said vat intermediate the ends thereof, said vat having apertures there-around for the flow into said chamber of liquid from the mix in said vat, the lower of said plungers being apertured for the flow of liquid therethrough, a drain pipe connected to the bottom of said vat, a forming device arranged in said vat transversely thereof adjacent said apertures, said forming device comprising spaced forming elements extending transversely of said vat, and means for moving said plungers toward each other to positions in limited spaced relation to said forming elements to form a resultant board between said plungers with said forming elements embedded therein.

13. An apparatus for making fiber boards from a thin watery mix containing organic fibers, comprising a vertical vat, plungers reciprocable in said vat, means for introducing the mix into said vat between said plungers when the latter are moved away from each other, a forming device comprising a frame corresponding in shape and size to the cross-sectional shape and size of said vat, a door carried by said vat and adapted to be opened for the introduction of said forming device into said vat transversely thereof, said vat being provided with guideways for guiding and supporting said forming device in said vat, means for moving said plungers toward each

2,428,512

9

other to form a resultant board between said plungers, and means intermediate the ends of and extending around said vat for draining liquid therefrom.

WILLIAM G. BRUBACHER.
